METHOD OF HEAT TREATING METAL BODIES

Homer W. Jones, Westfield, N. J., assignor to
The Linde Air Products Company, a corporation
of Ohio

Application August 24, 1937, Serial No. 160,576

3 Claims. (Cl. 148—21)

This invention relates to a method of heat-treating a portion of a metal body, and more particularly to a method of heat-treating, by flame hardening, a corner of a hardenable metal body such as a steel die. The term "corner," as used hereinafter and in the appended claims, includes not only the meeting edge or merging portion of two angularly disposed or intersecting surfaces but also the portions of the surfaces adjacent the meeting edge and a portion of the interior of the body immediately adjacent the meeting edge.

The method of this invention will be described herein chiefly as it may be applied to the hardening of the corners of steel bodies or machine tool parts which are subjected to high stresses, such as large dies of the type used in the manufacture of bodies and tops of automobiles. The size of the sheets of metal which are utilized in forming the bodies and tops of automobiles necessitates the use of large steel dies, the hardening of which by previous methods has been difficult and expensive.

The hardening of such dies has heretofore been accomplished by either ordinary heat-treatment or case-hardening methods. In ordinary heat-treating operations, the entire die is placed in a furnace and heated to a temperature above the critical, whereupon the die is quenched to produce a hardened structure. This method produces a hardened structure throughout the whole of the die, and it is necessary to temper the hardness by a further heat-treatment so that the interior of the die will have sufficient ductility to withstand the impact stresses produced by shearing or cutting metal. The entire die is heated in each operation, and it is impossible to attain simultaneously a maximum hardness in the wearing portions of the die and a maximum ductility and toughness in the interior of the die. Such heat-treatment also distorts the die, necessitating the use of special expedients to assure the production of an accurately sized and shaped die.

In ordinary case hardening operations, the entire die is heated in a carburizing box packed with a carburizing agent which will add carbon to a portion of the outer surface, and, after carburizing, the die is cooled to produce a hardened outer surface or case. After carburizing, it is necessary to reheat the die to relieve stresses produced by the previous operations. The entire die is heated in each operation, producing distortion, and the hardened case produced is usually so shallow that, in heavy service, it tends to break, crack, chip and spall.

In most instances, the greatest amount of wear

on a die occurs at and near its corners. Accordingly, for a maximum life, such dies should have tough bodies, a moderate hardness over the portions of the surface remote from the corners, and the greatest hardness at and adjacent to the corners.

The principal objects of this invention are to provide a method of hardening the corner of a steel die or other hardenable metal body which will produce a maximum hardness at the shearing edge without seriously impairing the ductility and toughness of the interior or body of the die; to provide such a method which will be facile, simple and economical; and to provide a method of flame hardening the corners of metal bodies which may be made automatic or semi-automatic.

According to this invention, successive portions of a die corner to be hardened are heated uniformly to a temperature within or above the hardening or "critical" range, and the portions so heated are cooled to harden the same and also to restrict the depth of hardening. The uniform heating of successive portions of the corner is effected by high temperature heating flames applied to each of the intersecting surfaces at places adjacent to but spaced from the meeting edge of said surfaces, the edge and the portion of the corner closely adjacent thereto being heated chiefly by conduction from the directly heated portions. Preferably, relatively wide heating flames having an equalized velocity front are used and are disposed transversely or substantially perpendicularly to the edge.

The invention will more readily be understood from the following description and the accompanying drawings, in which:

Fig. 1 is a perspective view of apparatus adapted for use in hardening a corner of a metal body;

Fig. 2 is a vertical sectional view of a corner of a metal body or steel die, illustrating the application thereto of relatively wide, elongated heating flames;

Fig. 3 is a longitudinal sectional view illustrating the application of a heating flame and cooling fluid to a surface of a metal body;

Fig. 4 is a bottom view of a heat-treating head forming part of the apparatus of Fig. 1;

Fig. 5 is a longitudinal sectional view of the head of Fig. 4, taken along the line 5—5; and

Fig. 6 is a transverse longitudinal sectional view of the head of Fig. 4, taken along the line 6—6.

Referring specifically to Fig. 1, apparatus comprising two heat-treating heads H and H', form-

ing part of blow-pipes B and B' are supplied with a combustible gas mixture and a cooling or quenching fluid by suitable fluid-control mechanisms and are positioned at a corner A of a metal body or steel die M. The heat-treating heads H and H' and blowpipes B and B' are supported in working position from a suitable carriage C by structure which includes means for independent adjustment of each head H and H' vertically and horizontally in a plane perpendicular to the corner to be treated, so that portions of each surface on opposite sides of the edge of the corner will be treated simultaneously. The supporting structure also includes means for moving the heads H and H' simultaneously, and longitudinally of the corner to be treated, to permit progressive treatment of successive longitudinal portions of the corner manually, automatically, or semi-automatically. 20 The carriage C travels along a suitable track T supported at a convenient height above the metal body M.

The heat-treating heads H and H' may be of any type adapted to project a heating flame F upon a portion of the corner of the metal body M adjacent to, but not at, the edge of the corner, and thereafter to project a stream of quenching fluid W upon the heated portion, as indicated in Fig. 3. It is preferred, however, 25 to use a head of the type shown in Figs. 4-6, which projects a ribbonlike flame having an equalized velocity front, in a manner subsequently described. A flame of the latter type heats the treated portions uniformly and, as shown 30 in Fig. 2, produces a hardened corner portion A' of the desired depth and hardness, at the same time leaving the unhardened interior of the metal body or die sufficiently tough and ductile to withstand severe impact stresses. The construction 35 of this preferred type of head is described and claimed in my co-pending application Serial No. 160,575 filed concurrently herewith.

The fluid control mechanisms of the blowpipes B and B' may be any suitable mechanisms for 40 supplying controlled amounts of a combustible gas mixture and a cooling fluid to the heads H and H'. Preferably, the control mechanisms include means for controlling the calorific value of the combustible gas mixture, so as to control 45 the temperatures of the flames F and F', for reasons which will be explained below. A control mechanism which, by reason of its simplicity, availability, and effectiveness, is a suitably modified oxy-acetylene blowpipe body of the type that permits control of flame temperatures by mixing 50 fuel gas, oxygen, and air in various proportions. Each blowpipe should be provided with valves 55 10 or 10' and 11 or 11' for controlling the flow of fuel gas (preferably acetylene), and oxidizing gas, respectively, to a conventional mixer and subsequently through a conduit 14 or 14' to the head H or H'. Conventional means (not shown) are preferably provided for supplying either pure oxygen or oxygen-nitrogen mixtures of controllably variable composition and pressure to the inlets of the valves 11 and 11'. If desired, air may be admitted to the oxygen stream below the valves 11 and 11'. Other conventional means (not shown) are provided to supply fuel gas at 60 a controllably variable pressure to the inlets of the valves 10 and 10'. Valves 12 and 12' may be provided to control the flow of quenching fluid, usually water, through conduits 13 and 13' to the heads H and H'.

75 The carriage C, which supports the blowpipes

B and B' and heat-treating heads H and H' comprises a frame or case 20 provided with wheels or runners, or both, to permit travel along the track T. The carriage may be propelled either by hand or by a motor, as desired. Upon the case 20 there is mounted a slide 21 which is rotatable about an axis perpendicular to the top of the case 20. By a rack and pinion device operated by a handwheel 22, the slide 21 may be moved back and forth horizontally across the top of the case 20. On one end of the slide 21 there is a post 30 provided with an elevating screw 31 operated by a handwheel 32, and a vertical slide, in threaded engagement with the elevating screw 31 and guided by the post 30, is provided with an arm 33. The arm 33 may be raised and lowered vertically with respect to the top of the case 20 through operation of the handwheel 32 and elevating screw 31. Pivoted secured at right angles to the end of the arm 33 20 is a second arm 34, and pivotally secured at right angles to the second arm 34 is a supporting member 35. The blowpipe B is directly and rigidly secured to the member 35, and the blowpipe B' is supported by the member 35 through suitable 25 adjustable sliding supports 36 and 37 disposed at right angles to each other. By adjusting the angular positions of the slide 21, arm 34, and member 35, the blowpipe B and B' and the heat-treating heads H and H' may be set at any 30 desired angle to the work. By operating the handwheels 22 and 32, horizontal, and vertical adjustment of the blowpipes B and B' and the heads H and H' may be effected, and horizontal and vertical adjustment of the head H' independent of the head H may be obtained by turning handwheels 36' and 37' to adjust the sliding supports 36 and 37, respectively.

In use, the heat-treating heads are positioned, one on each side of a corner, with the flames applied to a portion of each of the surfaces of the corner, the portions directly heated in this manner being spaced from the edge E of the corner, as shown in Figs. 1 and 2. A jet or jets W of water or other quenching fluid is projected simultaneously with each heating flame and rearwardly thereof, away from the direction of travel of the heat-treating heads H and H', as indicated in Fig. 3, so that the entire length of the corner may be hardened in a single pass. The edge E of the corner, 50 is heated and cooled chiefly by conduction from and to the directly heated and cooled parts of the corner, and thereby attains substantially the same hardness as the directly heated and cooled parts.

While it will usually be necessary to harden only a single corner of a metal body or die, in some instances it may be desirable to harden a plurality of corners, two adjacent corners, or two adjacent corners and the surface common to the corners, such as in the case of punches used in producing elongated slots in sheets of metal. In such instances, a corner A'' of the metal body M of Fig. 2 may be hardened simultaneously with the corner A by two blowpipes and heads (not shown) similar to the blowpipes B and B' and heads H and H' of Figs. 1 and 2. These additional heads may be supported from and moved by the carriage C by suitable supporting means similar to the supporting means for blowpipes B and B', and the heads disposed in substantially the same relation with respect to the corner A'' as the heads H and H' are disposed with respect to the corner A. In other instances, it may also be desirable to harden the entire surface common 75

to the corners A and A'', and for that purpose a head H'' (shown partially in full and partially in dotted lines in Fig. 2), head H, and a head H''' (shown in dotted lines in Fig. 2) may direct heating flames F'', F, and F''', respectively, onto the surface common to the corners A and A'' and the surfaces of the corners intersecting the common surface. The head H'' is wider than the head H' and directs the elongated flame F'' over the greater portion of the surface common to the corners, the flame F'' preferably being applied to this surface in such a manner as to heat chiefly or primarily by conduction the edges E and E' of the corners A and A'', respectively. The flame 15 F''' is applied to the corner A'' from the head H''' in a manner similar to that in which the flame F is applied to the corner A. The heads H, H'', and H''' may be supported from the carriage C by suitable means similar to the supporting means for heads H and H', and as the heads H, H'', and H''' are moved simultaneously by the carriage C, they are also adapted to direct cooling jets upon the heated corners and common surface immediately following the heating flames, 20 in the manner previously described.

In most instances, the mass of metal to be treated will be sufficiently small that a very high flame temperature and a brief heating period will produce the desired hardening, and in such instances it will be most advantageous to use a heating flame of acetylene and pure oxygen. In some instances, however, the section to be treated will be so heavy that the "mass effect," encountered in heat-treating heavy sections of metal, 25 will make it more desirable to use a lower flame temperature and a longer heating period—to permit the heat to soak into the metal without danger of overheating—and in such an instance it is preferred to lower the flame temperature by diluting the oxygen with nitrogen, as by mixing air with the oxygen used for combustion of the acetylene. A fuel having a lower calorific value than acetylene may be used, of course, but such a fuel does not permit the attainment of the high temperatures ordinarily desired and is therefore less flexible in its application.

To obtain a maximum uniformity of hardening, it is desirable to use a ribbonlike flame having an equalized velocity front and an inner cone of 30 substantially constant height. Such a flame may be produced by delivering gas at a substantially uniform pressure over the length of an elongated orifice in the heat-treating heads H and H'. Such a flame may be produced by the preferred type 35 of head illustrated in Figs. 4-6, to which reference is now made.

The head H of the blowpipe B, as in Figs. 4-6, comprises a front block 40, a rear block 41, and a U-shaped gasket 42 clamped therebetween. 40 The rear block 41 is provided with an inlet passage 43 to which the conduit 14 is connected. The passage 43, which extends centrally through the rear block 41 in a direction perpendicular to the inner surface thereof terminates in a chamber 45; the chamber 45 preferably having a concave back surface 46 conforming in shape to a right segment of a cylinder. The inlet passage 43 preferably terminates at a point adjacent the greatest distance between the concave surface and 45 that opposite thereto, and substantially in the center of the concave surface. Leading from the chamber is a relatively thin and wide passage 47 terminating in an elongated orifice 48, the passage 47 being formed between the blocks 40 and 41 by the opening in the gasket 42, which

preferably extends to a point 49 somewhat beyond the entrance of the inlet passage into the chamber. The width of the passage 47 and orifice 48 may be varied at will by using U-shaped gaskets having openings of various widths.

The combustible mixture is led into the chamber 45 by the inlet passage 43 and is projected therefrom, in a direction angular to that of its inlet, through the relatively thin passage 47 and the elongated orifice 48, thereby forming a relatively wide, elongated jet extending across the width of the orifice 48 and producing a flame having an inner cone of substantially uniform height. Preferably, the angle between the passage 43 and the passage 47 is approximately 90°.

The rear block 41 is provided with a cooling fluid inlet 50 to which the conduit 13 is connected. Two passages 51 and 52, one on each side of the combustible mixture inlet passage 43, lead from the cooling inlet 50 to a chamber 20 54 disposed within the rear block 41 adjacent the orifice or front end thereof. The chamber 54 may be a hole drilled from the side of the block, the outer end thereof being closed by suitable means, such as a plug 55.

To direct the cooling fluid upon a surface portion previously heated, a plurality of fluid discharge passages 56 terminate in a row of discharge orifices 57 spaced from and preferably parallel to the combustible mixture orifice 48. 30 For more uniform quenching, the discharge passages are preferably sufficiently close together so that the cooling jets projected therefrom will merge laterally to form a continuous wide cooling stream of substantially the same width as the relatively wide heating jet. The fluid discharge passages 56 are preferably inclined away from the combustible mixture discharge passage, suitably at an angle of approximately 5°, to prevent the cooling fluid, after being directed upon the surface, from interfering with the heating flame. The cooling fluid, when utilized in the above manner, not only prevents the blowpipe head from becoming overheated, but also cools previously heated portions of the metal body M.

The blocks 40 and 41 are provided with a plurality of holes 58 in which bolts 59 are inserted to clamp the gasket tightly between the blocks.

It will be understood that other blowpipes than those described may be used in carrying out the method of this invention; that the blowpipes may be held stationary, and the metal body or die moved relatively thereto; and that other changes may be made which will not depart from the spirit and scope of this invention.

What is claimed is:

1. A method of heat treating a corner of a ferrous metal body which comprises directing a wide high temperature heating flame against a portion of one of the surfaces forming said corner; directing a second wide high temperature heating flame against a portion of the other surface forming said corner, such second-named portion being disposed directly opposite the first-named portion on the other side of the edge of said corner, and said wide high temperature heating flames being of substantially the same width, disposed in the same plane perpendicular to said edge, and so directed that the portions of said surfaces directly heated are spaced from the edge of said corner substantially equal distances and at such distances that said edge will be heated chiefly by conduction of substantially the same amounts of heat from each of the portions directly heated and will be heated to the same tem- 75

- perature as the portions directly heated; cooling the heated surface portions simultaneously and immediately after such heating by directing wide independent and coplanar streams of cooling fluid simultaneously against such heated surface portions; and similarly heating and cooling successive portions of said corner so as to harden the same.
2. A method of heat treating a corner of a ferrous metal body which comprises applying localized high temperature heat simultaneously to portions of each of the surfaces of said corner, such portions being disposed on opposite sides of the edge of said corner and also being spaced from the edge of said corner, so as to heat said spaced portions directly and to heat said edge and parts of said corner closely adjacent thereto chiefly by conduction from the portions directly heated; cooling the heated surface portions of

said corner immediately after heating; and similarly heating and cooling successive surface portions of said corner to harden the same.

3. A method of heat treating adjoining portions of two angularly disposed and merging surfaces of a ferrous metal body which comprises applying localized high temperature heat to said surfaces at points directly opposite each other on each side of and spaced from the merging portion of said surfaces so as to heat simultaneously a portion of each of said surfaces directly and to heat the merging portion of said surfaces chiefly by conduction from the portions heated directly; cooling the heated surface portions simultaneously and immediately after such heating; and similarly heating and cooling successive portions of said surfaces to harden the same. 10 15

HOMER W. JONES.
